UNITED STATES PATENT OFFICE.

OTTO KARTZMARK, OF NEW YORK, N. Y.

GUARD MECHANISM FOR PUNCH-PRESSES.

1,086,059.

Specification of Letters Patent.

Patented Feb. 3, 1914.

Application filed September 15, 1911. Serial No. 649,492.

To all whom it may concern:

Be it known that I, OTTO KARTZMARK, a citizen of the United States, residing in the borough of Brooklyn, city of New York, county of Kings, and State of New York, have invented certain new and useful Improvements in Guard Mechanisms for Punch-Presses, of which the following is a specification.

10 Broadly considered, my invention relates to devices for safe-guarding operators from injury by machinery. It is, however, particularly adapted for use in connection with punch presses, and it will be described in 15 that connection.

The general object of my invention is to provide a new and improved guard mechanism which can readily be applied to a punch press, and which will so limit the 20 operation of the press that it is impossible for the operator to bring the dies together while his hand is between the dies, or in any other dangerous position.

In most punch presses, the controlling device by which movement of the reciprocating member is regulated is connected to an actuating lever which is often arranged for operation by the foot of the workman. Although my invention is not limited to use with such 25 presses, it is particularly adapted for them, since its working parts can easily be interposed in the connection between the controlling device and the actuating lever.

My invention will be fully understood, 30 and its many advantages will appear from the following description of one embodiment thereof, taken in connection with the accompanying drawing, in which—

Figure 1 is a side elevation of a punch 35 press having my invention attached thereto; Fig. 2 is a fragmentary sectional view showing the manner in which two parts of the device are connected together; Fig. 3 is a front elevation showing the principal elements of the guard mechanism; Fig. 4 is an elevation of the bracket or base upon which the movable elements in the guard mechanism are supported; Fig. 5 shows the rotatable member which carries the guard; Fig. 6 shows the rotatable member which cooperates with the member shown in Fig. 5; Fig. 7 shows a lever operated by the member shown in Fig. 6; Fig. 8 is a section on the

line 8—8 of Fig. 6, but with the holding bolt in place; Fig. 9 is a front elevation showing an adjustable connection employed with my guard mechanism; Fig. 10 is a section on the line 10—10 of Fig. 9, and Fig. 11 is a section on the line 11—11 of Fig. 9.

Like parts are referred to throughout the several views by the same reference characters.

The press illustrated in the drawings is of a well-known form having two supporting standards 15 upon which is mounted the body 16 of the press. This body is adjustable in a well-known manner, in order to permit the bed plate 17 of the press to be used either horizontally or inclined, as shown. The fly-wheel of the press is indicated at 18, mounted upon a shaft 19 journaled in the top of the body 16. The reciprocating element of the press is indicated at 20, and carries a die member 21 which cooperates with the die member 22 secured to the bed plate 17 of the press.

The driving connection between the reciprocating element 20 and the shaft 19 is not shown, but is to be understood as of any well-known form controlled by the operator in a well-known manner. For the present purposes, it is only necessary to say that the starting and stopping of the reciprocating element of the press is effected through the medium of a rod 25 connected to a latch member 26 forming part of the controlling mechanism. The lever 26 is shown in Fig. 3, and it is to be understood that when said lever is in the position shown in full lines, the fly-wheel 18 revolves without causing movement of the reciprocating element of the press; and that when said lever 26 is in the position shown in dotted lines, the connection between the fly-wheel 18 and the reciprocating member of the press becomes effective and the operation of the press takes place. Ordinarily, the rod 25 extends downwardly to a lever 28 pivoted at 29 in the frame 15, and the workman controls the operation of the press by moving the lever 28 with his foot.

What has been described up to this point is a well-known form of press. I will now proceed to describe my new and improved guard mechanism, and the manner in which the same is applied to a press of the type

just described. It will, however, be understood that my invention is equally applicable to other styles of press, with only slight modifications such as will be obvious to those skilled in this art.

The moving elements of my guard mechanism are interposed in the connection between the actuating lever 28 and the lever 26 of the controlling mechanism. In order that my guard mechanism may be easily applied to the press, I provide a base or bracket, shown particularly in Figs. 3 and 4. This base may be of any suitable form, and as shown, comprises a circular portion 36, from which extends an arm 37 having therein holes 38 through which bolts may be passed to secure the base to the press. Extending from the middle of the circular portion 36 of the base is a perpendicular stud 40 upon which the movable members 46 and 65 of the guard mechanism are pivotally supported, as hereafter described. The base carries a perpendicular lug 41 which extends a distance about equal to the thickness of the member 46, shown in Fig. 5, hereinafter described; and a perpendicular lug 42 extends outwardly from the arm 37, as shown. Extending from the round portion 36 is a radial arm 43 carrying a perpendicular stud 44 upon which the bell crank lever 72 shown in Fig. 7 is pivotally supported, as hereafter described. Supported on the stud 40 of the base is a member 46 of the form best shown in Fig. 5. This member 46 has a radial projecting socket 91, in which lies a bar 47 which is rigidly secured to the socket by bolts 48 which pass through holes 49 in such socket (see Fig. 1). These bolts have shoulders, as shown in Fig. 8. The guard proper may be of any suitable form, and, as shown in Figs. 1 and 3, comprises a U-shaped guard member 52 supported at about its middle by a bracket 53 which is secured to the end of the bar 54. As shown in Fig. 2 the bar 54 has one edge notched or toothed. This bar passes through a clamp 55. A channel bar 56 also passes through the clamp at right angles to the bar 54. The clamp 55 is provided with a screw 57 by means of which the teeth on the bar 54 are forced against the channel bar 56, thereby producing a rigid connection between the bars 54 and 56, while at the same time permitting adjustment of either of said bars longitudinally in the clamp. The channel bar 56 is connected to the bar 47 by means of a clamp 58 adjustable on the bar 47 in a manner obvious from Fig. 1. Of course, the construction of the guard, as just described, may be modified in many respects, and I have described it thus particularly merely because I believe that the arrangement which I have shown is a highly satisfactory one, since, while it permits ad-

justment of the guard member 52 in three directions, it still holds it firmly in position while the press is in operation.

Referring to Figs. 4 and 5; the rotary movement of the member 46 is limited in one direction by the engagement of the shoulder 60 against the lug 41; and in the other direction by the engagement of an adjustable screw 61 against the lug 42. The screw 61 passes through a radial lug on the round portion of the member 46, and said screw may be locked in position by a lock-nut 62.

Mounted on the stud 40 outside of the member 46, is a member 65, of the form best shown in Fig. 6. At one end, the member 65 is provided with a radial extension 92 with a recess 93 which covers the end of the bar 47. This extension 92 is wider than the bar 47 and is provided with slots 66 through which pass the shoulders on the bolts 48 which secure the bar 47 to the member 46. The radial projection of the member 65 is yieldingly maintained with reference to the radial position of the bar 47 and the member 46, by means of a leaf spring 67 arranged at one side of the bar 47 in the recess 93 of the member 65, as shown in Fig. 6. The member 65 has a radial lug 69, in which is mounted a perpendicular pin 70, which engages with a cam slot 71 in a bell crank lever 72, shown in Fig. 7. This bell crank lever 72 is pivotally supported on the stud 44 which extends from the base into the hole 73 in said bell crank lever. The member 65 is also provided with an extension 75, to which, by means of a hook 76 is secured a spring 77 which is connected to a pin 78 on the press frame. The spring 77 tends to hold the parts of the guard mechanism in the position shown in full lines in Fig. 1. The rod 25, leading to the controlling mechanism of the press, is pivotally connected to the lever 72 by means of a pin passing through a hole 80, as shown in Figs. 1 and 7. A rod 81 leads to the actuating lever 28 and is pivotally connected to the member 65 by a pin which passes through a hole 82 in a lug extending from the side of the extension 92, as shown in Fig. 1. The members 46 and 65 are held in position on the stud 40, by means of a nut 94.

In order to permit adjustability of the bed of the press upon its standards, the connection between the actuating lever 28 and the member 65 must be adjustable; and in Figs. 1, 9, 10 and 11 I have illustrated an adjustable connection which I have found to be very satisfactory. This connection comprises two parallel screw threaded rods 81 and 83, which are connected together by the device shown in Figs. 9, 10 and 11. This device comprises a nut 88 on the rod

81, and a similar nut 87 on the rod 83, said nuts being secured together by a screw 90 which passes freely through the nut 87 and screws into the nut 88. Each nut has a portion of its side removed, which will expose a portion of the threads of the rod passing through that nut, and each nut has a tongue 95 adapted to fill the cut-away portion in the other nut and is threaded so as to engage the threads on the rod passing through that other nut, as clearly shown in Figs. 9, 10 and 11. With this arrangement, it is obvious that when the screw 90 is removed, the nuts 87 and 88 may each be independently screwed back and forth, each on its own rod, until said nuts are properly located to give the desired length of connection between the lever 28 and the member 65. The nuts are then brought together and the screw 90 inserted. Upon tightening up on the screw 90, the tongue of each nut is drawn into the cut-away portion of the other nut, and engages with the exposed portion of the threads on the rod carrying the other nut, an action which will tend to throw the screw holes in the nuts out of alinement with one another, thereby binding the screw 90 and holding the same tightly in the nuts. It is obvious that the construction of connection just described is a highly advantageous one in the service to which it is put, since it will not give way or shake loose under the severe jarring to which it is subjected in the operation of the press.

The relations of the lug 41 to the shoulder 60, and of the pin 70 to the cam slot 71, are such that, until the shoulder 60 has come into engagement with the lug 41 which is caused by the simultaneous rotation of the members 46 and 65, the pin 70 will move in that portion of the slot 71 which is concentric with the stud 40 upon which the member 65 is pivoted; at this point the member 46 can rotate no further, owing to the engagement of the shoulder 60 with the lug 41; and it is only by the further movement of the member 65 with reference to the member 46 which is permitted by the nature of the connection between these members, that the pin 70 is enabled to engage with the bottom portion of the cam slot 71 and move the lever 72. The guard 52 should be so set that it is substantially in engagement with the bed 17 of the press when the shoulder 60 of the member 46 is in engagement with the lug 41. If the guard 52 is stopped before it reaches the bed, then the lever 72 will not be moved by engagement of the pin 70 with the bottom part of the cam slot 71 and the bell crank lever will not be turned upon its pivot until the guard 52 has reached the bed of the press. That is,—if the hand of the operator or anything else prevents

the guard from moving into engagement with the bed of the press, the movement of the member 65 with reference to the member 46 will take place before the pin 70 has reached the portion of the cam slot 71 at which the pin is effective to move the lever 72, and the press will not be operated. In other words,—the press cannot be actuated by the lever 28 unless the guard 52 is free to move into engagement with the bed of the press, which means that it is safe for the press to operate without injury to the operator. Furthermore, the guard will always remain in guarding position until the member 65 has moved sufficiently to rock the lever 72 and throw the controlling device of the press to stop position. The dies are, therefore, always guarded.

The screw 61 permits adjustment of the stroke of the guard mechanism, thereby enabling the operator to limit the movement of the lever 28 to merely what is necessary to move the guard satisfactorily and to operate the controlling device.

With some kinds of work, such as sheet punching, a guard is not as necessary for the protection of the operator as with those kinds of work which necessitate his constantly inserting his fingers between the dies. In my guard mechanism, by removing the bolt 48, the bar 47 and the whole guard can be removed, leaving a perfectly operative mechanism by which the press can be controlled in the usual manner.

In accordance with the provisions of the patent statutes, I have described the principle of my invention, together with the apparatus which I now consider to represent the best embodiment thereof; but I desire to have it understood that the apparatus shown is merely illustrative and that the invention can be carried out in other ways.

Having now described my invention, what I claim as new and desire to secure by Letters Patent, is—

1. A guard mechanism for punch presses comprising a movable guard member, a movable actuating member connected to said guard member through a yielding connection, means for moving said actuating member, and a motion transmitting device moved by said actuating member only when the latter is moved with reference to the guard member and when said guard member is in guarding position.

2. A guard mechanism for punch presses comprising a pivoted guard member, a pivoted actuating member connected to said guard member through a yielding connection, means for moving said actuating member, and a motion transmitting device moved by said actuating member only when the latter is moved with reference to the guard

member when said guard member is in the guarding position.

3. A guard mechanism for punch presses comprising a pivoted guard member, an actuating member pivotally arranged on the same axis as said guard member, a yielding connection between said guard member and said actuating member, means for moving said actuating member, and a motion transmitting device moved by said actuating member when the latter is moved with reference to the guard member and when said guard member is in the guarding position.

4. A guard mechanism for punch presses comprising a pivoted guard member, an actuating member pivotally arranged on the same axis as said guard member, a yielding connection between said guard member and said actuating member, means for moving said actuating member, and a cam connection between said lever and said actuating member whereby said lever is moved only when the actuating member is moved with reference to the guard member when the latter is in its guarding position.

5. In combination with a punch press having an actuating lever and a controlling device, a pivotally supported member, a guard carried thereby, another pivotally supported member, a yielding connection between said members, a connection between said second-named member and said actuating lever, and a connection between said second-named member and the controlling device operative only when the first-named member is in the position corresponding to the guarding position of the guard.

6. In combination with a punch press having an actuating lever and a controlling device; a guard mechanism comprising a base, a member rotatably mounted thereon, a guard carried by said member, another member rotatably mounted on said base, a connection between said last-named member and the actuating lever, a yielding connection between said rotatable members, and a connection between the second-named rotatable member and the controlling device operative only when the said first-named rotatable member is in the position corresponding to the guarding position of the guard.

7. In combination with a punch press having an actuating lever and a controlling device; a guard mechanism comprising a base, a member rotatably mounted thereon, a guard carried by said member, another member rotatably mounted on said base on an axis concentric with the axis of the first-named member, an adjustable connection between said last-named member and the actuating lever, a lost motion connection between said rotatable members, a spring tending to hold said rotatable members in a cer-

tain position with reference to one another, a lever connected to the controlling device, and a cam connection between said lever and the second-named member whereby said lever is moved only when the second-named member is moved against the tension of the spring with reference to the first-named rotatable member when the latter is in the position corresponding to the guarding position of the guard.

8. The combination, with the driving-mechanism of a machine, and a guard for moving parts of the machine; of a manually-operable member for throwing the guard and the driving-mechanism successively into operation, and connections between the manually-operable member and the driving-mechanism and the guard, said connections being adapted, during the first part of the operative movement of the manually-operable member, to move the guard fully to operative position without movement of the driving-mechanism, and thereafter, during continued movement of the manually-operable member, to throw the driving-mechanism into operation without further movement of the guard.

9. In combination with a machine having driving-mechanism, and controlling-mechanism, for throwing the driving-mechanism into operation, including a manually-operable member; a guard for moving parts of the machine, and connections between the guard and the controlling-mechanism whereby the guard is moved to operative position during the first part of the movement of the manually-operable member; the controlling-mechanism having lost-motion between the driving-mechanism and the manually-operable member whereby substantial movement of the driving-mechanism is avoided until the guard has been moved to operative position, and the connections between the guard and the controlling-mechanism including a yielding device to permit continued movement of the controlling-mechanism after the guard has been arrested in operative position.

10. In combination with a machine having driving-mechanism, and controlling-mechanism, for throwing the driving-mechanism into operation, including a manually-operable member; a guard for moving parts of the machine, and connections between the guard and the controlling-mechanism including yielding means for moving the guard to operative position during the first part of the movement of the manually-operable member, and positive means having lost-motion during said first part of the movement but adapted to prevent the further movement of the controlling-mechanism when the guard is arrested short of operative position; the controlling-mechanism

having lost motion between the driving-mechanism and the manually-operable member whereby substantial movement of the driving-mechanism is prevented during said

5 first part of the movement of the manually-operable member.

This specification signed and witnessed this 13th day of September 1911.
